UNITED STATES PATENT OFFICE.

CARL RUDOLPH KRONE, OF OAKLAND, CALIFORNIA.

RADIO VACUUM TUBE SOCKET.

Application filed January 17, 1924. Serial No. 686,865.

This invention relates to radio apparatus and concerns the particular construction of sockets for confining audion and amplifier bulbs or vacuum tubes.

5 The objects of my invention are to provide a socket which will cooperate with the base of standard tubes and afford means of elastically supporting within the socket such a tube selectively in either contact or break 10 positions of terminals, also means of automatically locking this socket against casual removal of the tube from the socket through vibration or inept manipulation.

The above objects are realized in my 15 socket construction shown in the drawings, and in which Figure 1 is a perspective view of my socket, Figure 2 is a fragmentary view in perspective of the upper part of the socket omitting the retaining ring, Figure 20 3 is a sectional elevation of Figure 1 as seen from the line 3—3 thereof, showing the lower portion of a standard bulb in alignment above the socket, Figure 4 shows my improved locking slot applied to the end of a 25 socket, and Figure 5 is a schematic plan of the same indicating the path of an imaginary center of a pin on its transit from one fixed point of lodgment within the slot to the other.

30 Before describing my socket in detail attention is called to the present general construction of the base of most radio bulbs as indicated in Figure 3, where (1) represents the bulb, (2) the base, (3) a plurality of 35 terminals for the bulb elements and adapted to contact the spring terminals (4) extending over the socket space from the binding posts (5) secured to the insulating plate (6) at the lower end of the socket tube (7).

40 The base (2) of the bulb has an aligning pin (8) which fits into a slot in the socket for aligning the proper terminals (3) and (4) when the base of the bulb is in the position of contact within the socket.

45 This aligning is accomplished by the use of a bayonet joint slot (9) with a notch (10) as indicated in Figure 2 from which it will be readily understood that the radio tube may be inserted or withdrawn as the pin (8) is locked in, or withdrawn from, the 50 notch (10).

This method, however, makes it necessary to remove the bulb entirely from the socket in disconnecting it from the terminals and 55 to provide a place for it when so removed, as it is easily injured. Under conditions of

special stress as on board ship, moving trains and other vehicles there arises danger for the tube to jar out and fall from the socket.

My improvements involve a lengthening 60 of the axial slot (9) so that the tube may be pushed in and out to make or break the contacts, a nonconductor washer (11) resting upon the springs (4) and supporting a spiral spring (12) which on its part gives 65 continuous elastic support to the base of the tube and normally tends to push it away from the terminals (4) and against the notches of the slot (9), and a retaining device or ring (13) for preventing the pin 70 (8) and the tube base (2) from being forced clear out of the socket.

This ring (13) is shown in Figures 1 and 3 as applied to a standard radio tube socket (7) and secured by a thumb screw (14) 75 threaded into the ring, its free end registering in a hole (14') in the side of the standard socket.

In the Figure 3 the relation of the ring 80 to the socket tube is shown. A shoulder (15) formed on the ring rests on the edge of the socket tube and by a notch (16) registering with the slot (9) of the socket tube extends this slot as proposed. This increase indicated at X in Figure 3 permits the aligning pin to be pushed beyond the original 85 confines of the socket, whereby the terminals (3) are separated from the contact springs (4) of the socket, while the bulb remains confined within the socket. 90

To entirely remove the radio tube or to insert it, the thumbscrew (14) is unscrewed far enough to clear it from the hole (14') in the socket tube, then the ring (13) is lifted vertically upward until the transverse slot 95 (18) clears the edge of the socket tube whereby to complete above the edge of the socket a passage between the two axial slots (9) and (17) along which the aligning pin (8) of the tube may be pushed out of the 100 socket thus freeing the bulb for removal.

When the ring is put back into place the rim of the socket closes again the passage along the slot (18).

If, before the ring was pushed back into 105 place, the bulb was inserted into the socket, and the aligning pin successively entered the slots (17), (18) and (9), and if then the ring was pushed back into place it will be found that the aligning pin (8) remains 110 elastically supported at the notch (16) and that the terminals (3) of the bulb are not

in touch with the contact springs (4) of the socket.

To make contact between the terminals (3) and (4) the bulb is pushed down against the opposing spring pressure, causing the aligning pin to descend in the slot (9), then turned toward the notch (10) of the slot and released, whereby the spring (12) is made to hold the aligning pin against the notch (10). It must not be overlooked that, when the pin is lodged at the notch (10), the contact springs (4) of the socket bear against the terminals (3) of the bulb adding security to its support.

In Figure 4 is shown my locking slot device modified as it would appear if it were made integral with the socket tube thereby doing away with an auxiliary ring and its attachment to a standard socket. The various parts of the slots described and functioning similarly are similarly numbered and primed as they are also similarly numbered and primed in Figure 5.

Of course, there being no other movable parts and no material wherewith to close the slot (18'), the security of lodgment of the aligning pin within the socket after it has, for any cause, left the notch (10') depends upon the upward pressure of the spiral spring (12) against the base of the bulb and upon the manner in which this pressure indirectly affects the urge of the aligning pin in its transit from one fixed place of lodgment within the socket to the other.

To prevent the escape of the aligning pin through the transverse slot (18'), at the

point where the latter slot opens the slot (9') intermediate its ends, I provide for a notch (19') and the forward projections (20') and (21') one above the other, as shown in Figure 5, which tend to direct the path Y of the pin away from the opening of the slot (18') and clear of any diverting obstruction and causing the aligning pin to arrive and safely lodge at the notch (16') of the slot (9') until intentionally removed by manipulation along the projection (21'), the slots (18') and (17'), or is returned to notch (10') of the slot (9').

I claim:—

In a device for use in connection with the vacuum tube socket of a radio circuit, a body capable of attachment to the socket so that it may be moved in a curvilinear path thereabout, means for holding the body in a position of fixed adjustment on the socket, and a slotted portion on said body having a part arranged for coaction with the bayonet slot of the socket so that the tube when adjusted to one position will be advanced and held in circuit making position with the contact elements of the socket, and when adjusted to a second position will permit the tube to be positioned in circuit breaking position, and the said slotted portion embodying a second part adapted for coaction with the bayonet slot of the socket so as to permit the removal of the tube from the socket, and means on said body for locking the tube in the socket when the body is in a position of determined or fixed adjustment.

CARL RUDOLPH KRONE.
